DESIGN FOR A GIFT NOVELTY

Mae A. Glazebrook, Memphis, Tenn.

Application October 16, 1937, Serial No. 72,245

Term of patent 3½ years

To all whom it may concern:

Be it known that I, Mae A. Glazebrook, a citizen of the United States, residing at Memphis, in the county of Shelby and State of Tennessee, have invented a new, original, and ornamental Design for a Gift Novelty, of which the following is a specification, reference being had to the accompanying drawing, forming a part thereof, in which

The figure is a perspective view of a gift novelty showing my new design.

I claim:

The ornamental design for a gift novelty, as shown.

MAE A. GLAZEBROOK.
